INSPECTION MEANS FOR SEALED
PACKAGESJames A. Sargeant, Fort Belvoir, and Jack R.
Wade, Jr., Alexandria, Va.

Application June 9, 1950, Serial No. 167,242

3 Claims. (Cl. 206—46)

(Granted under the act of March 3, 1883, as
amended April 30, 1928; 370 O. G. 757)

1

The invention described herein may be manufactured and used by or for the Government for governmental purposes, without payment to us of any royalty thereon.

Hermetically sealed and desiccated packages are used widely for highly diversified purposes, for example, for the shipment and preservation of dried or concentrated foodstuffs such as emergency rations for military purposes, for the packaging of medicaments or other commodities adversely affected by the presence of air or moisture, and for a wide variety of other applications where it is desired to protect the contents of the package from such access of air and moisture; and it is highly desirable to provide means whereby the interior of the package may be inspected without necessitating the disturbance of the wrappings or other coverings of the container, it being a convenient provision to install in the package adjacent to the container or to the contents of the package some mechanical means for indicating the maintenance of desired moisture- or air-tight conditions within the package itself.

An object of the present invention is to provide inspection means for a hermetically sealed package which will enable the preservation of the contents of the package in their original condition, and which will enable the checking of the conditions of hermetic sealing of a package without disturbance to the barrier, wrapping, or sealing means applied thereto.

A further object of the invention is the provision of a readily applied construction which itself will maintain a hermetic seal with the wrapper of the package and the contents thereof, and which will enable a readily visual inspection on the part of an observer of the conditions existent on the interior of the wrapping or package.

A still further object of the invention is the provision of improved mounting or supporting means for a moisture indicator which by a change of color, or otherwise, would designate to an observer an unwanted condition of humidity, air, or the presence of moisture inside of the wrapping or package.

Further objects of the invention will become apparent as the description proceeds, and the features of novelty will be pointed out in particularity in the appended claims.

The invention will be understood more particularly by reference to the accompanying drawings which show an illustrative embodiment of the invention, in which

Fig. 1 is a perspective view of a hermetically sealed package provided with the features of the present invention;

2

Fig. 2 is a sectional elevational view taken on the line II—II of Fig. 1, looking in the direction of the arrows; and

Fig. 3 is an expanded perspective view showing parts of the construction in disassembled relation.

Referring more particularly to the drawings, reference character A represents a hermetically sealed package provided with a moisture- and vapor-proof wrapping B, and a seal C. The illustrated embodiment of the invention embraces an inspection window or port which is indicated at E, and which can be installed in any flexible or rigid barrier material either at the time of the initial packaging or any time after the packaging has been completed.

The invention comprises a frame assembly including a short tubular member 5 that is threaded externally, as is indicated at 7, and that is provided with an end flange 9 which is designed to be received behind a moisture- and vapor-proof barrier material 11 which may be either the wrapping B or a waxed or otherwise water- or moisture-proofed container for articles to be protected. A sealing washer 13 fits over the threads 7 against the end flange 9 of the threaded cylinder 5, this end flange forming a backing ring for the assembly; and the said barrier material 11 engages the sealing washer 13. It will be understood that the end flange 9 and the washer 13 are inserted in the barrier material by cutting a hole in the latter sufficiently large to permit insertion of the flange 9 and retaining washer 13 while leaving enough of the said barrier material peripherally of this opening to overlie the washer 13. Preferably, the outside surface of the flange 9 and the inside and outside of the barrier material 11 adjacent to the hole are coated with a quick-drying, water- and moisture-proof adhesive cement, and a retaining gasket 15 then is slipped over the threads 7 and brought tightly against the outside of the barrier material 11 and locked tightly thereagainst by a locking ring 17, which clamps the barrier material 11 between the washers 13 and 15. The locking ring 17 preferably has its inner surface adhesively coated with the said quick-drying, moisture- and air-proof adhesive cement.

The locking ring 17 may be either round, as shown, and provided with peripheral, diametrically disposed holes 19 for the reception of a spanner wrench for tightening it on the threads 7 against the washer 15; or the locking ring 17 may be hexagonal for gripping with a usual type of jaw wrench for tightening the ring 17 against the washer 15. Another sealing gasket 21 then is slipped over the threads 7, and when as-

sembled, it is engaged by an internally threaded cap member 23 having a peripheral flange 25 which projects over the washer 21, and which carries a transparent cover plate 27 that is secured in the flange 25 in any well-known manner, or the cap member 23 may be made of an integral transparent plastic material. The transparent cover plate 27 may be integral with the cap or cover 23 or it may be a separate transparent cover glass mounted in the flange 25 in a manner similar to a watch crystal, with a layer of cement interposed as a water- and air-proof seal if such is found to be desirable. The aforesaid use of cement between the various joints is largely optional where the gaskets or sealing rings 13, 15 and 21 are employed, as these gaskets may be made of any of a number of compressible resilient materials that are available as is well-known for the purpose of making the assembly moisture- and air-tight. The use of such gaskets, with omission of the cementitious seals as mentioned above, offers the advantage of enabling the viewing assembly to be demounted if desired without destruction of any of the parts including the barrier material 11, and an efficient seal is obtained with the use of the sealing gaskets or rings 13, 15 and 21. Thus, a barrier wrapping with the window assembly of this invention installed and using gaskets or sealing rings 13, 15 and 21, but no cement, was placed in a cold chamber at -80°. It was found that the cold had no effect on the window assembly. Also, a barrier with the window assembly installed and using gasket rings 13, 15 and 21 with no intervening cement, was immersed under a foot of water for a week, the barrier being waxed, but no cement or other extraneous material was employed on the window assembly. There was no leak through or around the window and the change of relative humidity was only one percent.

In order to observe any change in the humidity or moisture content behind the window assembly and water-proof barrier or wrapping B, the tubular cylinder 5 may be provided with a plurality of internal grooves 29, pairs of such grooves being diametrically oppositely disposed for the reception of the opposite legs 31 of a U-shaped spring clip carrier member that may carry a vial or other transparent container 33, in which is placed a quantity of anhydrous copper sulphate or other moisture indicator which will indicate a change in moisture content within the package A or behind the water-proof barrier wrapping B by a change in color of the indicator. The container 33 is mounted on the carrier in the line of vision through the transparent window 27. The ends of the legs 31 of the spring clip carrier are bent at about right angles, as is indicated at 35, to engage over the end of the cylinder 5, thereby retaining the clip against displacement during assembling of the parts of the window assembly.

It will be apparent from the foregoing that the improvements of the present invention furnish a water- and vapor-proof protection which is equal to any of the types and grades of barrier material being utilized and it provides means of visual inspection for the purpose of observing the condition of the contents packaged and of the water or vapor content of the atmosphere and/or desiccant contained within the dehydrated water- and vapor-proof packages, while providing access to the interior of the package, when so desired, for the purpose of application or replacement of desiccant, the installation or

servicing of relative humidity-indicating means, thermometer, or other instruments, and it will enable other forms of inspection of the contents packaged. The improved construction can be installed easily in existing water- and vapor-proof packages, as well as in new packages at the time of fabrication, and is of such a character that the services and time of a skilled technician are not required.

At the present time, prior to the advent of the present construction, packages formed of opaque barrier materials must be cut open in order to observe conditions of the contents packaged, or to replace the desiccant, or for any other purpose; and while there are some packages which are provided with a fixed window, these also must be cut open to accomplish necessary inspection and servicing, and in most instances the barrier material is damaged to the extent that satisfactory rescaling cannot be accomplished, thus requiring a complete dismantling and replacement of the barrier.

The preferred method of assembling the installation of the present invention will be apparent from the foregoing description. Thus, a hole of the size required to accommodate the end tubular cylinder 5 is cut into the barrier material, this hole being smaller in diameter than is the diameter of the backing ring flange 9, this opening being elongated if necessary to accept the backing ring flange 9 and the first gasket 13, the adjacent portions of the barrier material forming an annular apron which uniformly engages the said first gasket 13. This gasket 13 is of a yielding resilient material, such as fiber or impregnated cork packing or the equivalent, and is adapted to form a hermetic seal with the barrier 11. The second retaining or sealing ring or gasket 15 then is applied to the threads 7 of the tubular cylinder 5, and drawn up snugly against the barrier 11 by the ring 17. The clip carrying the humidity indicator 33, or other instrument, thermometer or the like, is inserted in suitable grooves 29 before insertion of the tubular cylinder 5 and retaining flange 9 behind the barrier material.

When the washer 15, which also is a yielding, resilient annular washer, of fiber or impregnated cork packing or the equivalent, is applied snugly to the threads 7, the barrier material 11 is clamped hermetically between the washers 13 and 15 by the locking ring 17, which is applied to the threads 7 and firmly tightened against the gasket 15, by the aid of a suitable wrench, such as a spanning wrench, inserted in holes 19, or a jaw-type wrench if the locking ring is square or hexagonal in shape. The resilient washer 21 then is applied to the threads 7 and snugly drawn against the locking ring 17, this washer 21 also being resilient for forming a hermetic seal with the locking ring 17 and also with the internally threaded end cap member 23, the internal threads of which are complementary threads 7 on the tubular cylinder 5, the washer 21 forming a hermetic seal between the cap member 23 and the remainder of the assembly. The transparent cover 21 desirably is made integral with the remainder of the cap structure of the whole being formed of an unbreakable, transparent, plastic material, rather than glass, which is liable to become cracked or broken in service, with attendant loss of moisture-tightness in the completed assembly.

It will be apparent from the foregoing description, that the improved inspection device of the

present invention provides means for the ready visual inspection of the condition and moisture content of the atmosphere and contents, in dehydrated moisture- and vapor-proof packages, and permits access to the interior of the package for application or replacement of desiccant, relative humidity indicators, instruments, and other inspections and related operation, and the construction is so designed that it can be installed either at the time the package is constructed, or it may be applied to packages already completed; and the invention provides, also, means of securing indicators, thermometers, or other instruments adjacent to a window or port within the interior of the package for convenient viewing from the exterior thereof; and the invention contemplates the inclusion within its scope of such modifications and changes in structural details as may be necessary to adapt it to varying conditions and uses, as defined by the appended claims.

Having thus described our invention, what we claim as new and wish to secure by Letters Patent is:

1. Inspection apparatus for viewing the interior of hermetically sealed packages including a hermetically sealed water- and vapor-proof barrier material and provided with an observation window in the said material, which comprises, in combination, an externally threaded, tubular cylindrical retaining member inserted in the said observation window and having an annular backing flange thereon adapted to receive the periphery of the said window, yieldable means on the retaining member for hermetically sealing the periphery of the said window against the backing flange, locking means received on the said retaining member for locking the sealing means against the periphery of the said window in hermetically sealed relation therewith, a viewing member including a transparent cover also mounted on the said tubular retaining member in alignment with the window and approximately coextensive in area therewith and hermetically sealed against the locking means and adapted to permit continuous visual inspection of the interior of the hermetically sealed package through the said window, and means carried by the said tubular retaining member for mounting in the said package adjacent to the said window and in line of vision with the said transparent cover, continuously indicating means for indicating to an observer atmospheric conditions within the said container while enabling substantially uninterrupted viewing of the interior and contents of the container.

2. Inspection apparatus for viewing the interior of hermetically sealed packages including a hermetically sealed water- and vapor-proof barrier material and provided with an observation window in the said material, which comprises, in combination, an externally threaded, tubular cylindrical retaining member inserted in the said observation window and having an annular backing flange thereon adapted to receive the periphery of the said window, sealing means mounted on the retaining member for hermetically sealing the periphery of the said window against the backing flange, locking means threadedly received on the said retaining member for locking the sealing means against the periphery of the said window in hermetically sealed relation therewith, a viewing member including a

transparent cover also mounted on the said tubular retaining member and hermetically sealed against the locking means with the transparent cover in alignment with the said window and substantially coextensive in area therewith, and tensioned spring clip means mounted in the retaining member for mounting in the package adjacent to the said window and in line of vision with the transparent cover, indicating means for indicating to an observer atmospheric conditions within the said container while enabling continuous substantially uninterrupted viewing of the interior of the container and contents thereof, the inspection apparatus being adapted to be disassembled without impairment of the hermetic seals of the package.

3. Inspection apparatus for viewing the interior of hermetically sealed desiccated packages including a hermetically sealed water- and vapor-proof barrier material provided with an observation window therethrough for enabling viewing of the interior of the package, which comprises, in combination, a tubular, externally threaded retaining member mounted in the observation window and having an annular backing flange thereon adapted to receive the periphery of the said window, the said retaining member being provided interiorly with spaced oppositely disposed pairs of longitudinally extending grooves, a tensioned spring clip member mounted in oppositely disposed pairs of the said grooves, means mounted on the spring clip member for indicating to an observer atmospheric conditions within the sealed and desiccated package, a resilient washer mounted on the retaining member and positioned against the retaining flange, the said resilient washer receiving the periphery of the said window, a second yieldable washer mounted on the retaining member and engaging the periphery of the said window in hermetically sealing engagement therewith and with the said resilient washer, a locking ring threadedly mounted on the retaining member and snugly engaging the said second washer for maintaining the gasket hermetically sealed against the periphery of the window, a third resilient washer mounted on the retaining member in engagement with the locking ring, and a cap member threadedly mounted on the retaining member and hermetically sealed against the said third washer, the cap member including a transparent cover plate disposed in alignment with the window and having an area approximately commensurate with that of the window for enabling continuous viewing of the window and interior of the package to be observed and the atmosphere-indicating means carried by the retaining means.
